(57) **CLAIM**

The ornamental design for an instrument holder, as shown and described.

DESCRIPTION

FIG. 1 is a front, left, top perspective view of an instrument holder;

FIG. 2 is a front, left, bottom perspective view thereof;

FIG. 3 is top plan view thereof;

FIG. 4 is a bottom plan view thereof;

FIG. 5 is a right side elevational view thereof;

FIG. 6 is a left side elevational view thereof;

FIG. 7 is a front elevational view thereof;

FIG. 8 is a rear elevational view thereof; and,

FIG. 9 is a rear, top perspective view thereof.

The broken lines in the figures illustrate elements of the instrument holder that form no part of the claimed design.
